UNITED STATES PATENT OFFICE.

GEORGE VAIL, OF EMERADO, NORTH DAKOTA.

WINDMILL.

Application filed September 26, 1919, Serial No. 326,497. Renewed May 3, 1922. Serial No. 558,265.

To all whom it may concern:

Be it known that I, GEORGE VAIL, a citizen of the United States, and a resident of Emerado, in the county of Grand Forks and 5 State of North Dakota, have invented a new and Improved Windmill, of which the following is a full, clear, and exact description.

This invention relates to improvements in windmills, an object of the invention being 10 to provide an improved construction and mounting for a wind wheel, the latter having pivotal or partial rotary movement horizontally at its intermediate body portion and having blades or vanes extending from the 15 body portion located normally at an incline, certain of said blades or vanes counterweighted so that when they move in the position to be engaged by a draft of air, are caused to assume a vertical position trans- 20 versely while the other blades or vanes are caused to assume a horizontal position transversely and thus have a feathering action on the air until they reach a position where they in turn assume a vertical position transver- 25 sely so that a maximum of surface is presented at one side of the wheel to the draft of air and a minimum of surface is presented at the other side of the wheel to reduce the resist- 30 ance to the turning movement.

35 A further object is to provide an improved construction of wind wheel which is horizontally disposed and has a horizontal pivotal movement on a vertical drive shaft, which pivotal movement is controlled by the draft of air so as to bring the blades or vanes successively into position to receive the force of the draft of air.

40 A further object is to provide a device of the character stated, which is of extremely simple construction, which can be manufactured and sold at a reasonably low price, and which will be operated by a draft of air from any direction.

45 With these and other objects in view the invention consists in certain novel features of construction, and combinations and arrangements of parts, as will be more fully herein-after described and pointed out in the claims.

In the accompanying drawings:—

50 Figure 1 is a view in side elevation illustrating my improved wind wheel in a normal position when no draft of air is directed thereupon;

Figure 2 is an end view of Figure 1;

55 Figure 3 is a top plan view;

Figure 4 is a view in side elevation showing a position of the parts when a draft of air is directed against the wind wheel; and

Figure 5 is an end view of Figure 4.

1 represents a support and 2 a vertical drive shaft mounted in the support and having a relatively short horizontal shaft 3 at its upper end on which my improved wind wheel 4 is mounted. The wind wheel has a central body portion, the members of which 60 are positioned at a right angle to each other, as indicated by the reference numeral 12, and a bearing sleeve 5 is located at the angle of said body portion and mounted to turn or 65 partially turn on the shaft 3.

70 From the ends of the body portion 12 normally inclined blades or vain 6, 7, 8 and 9 project. These blades are arranged in pairs, the blades 6 and 7 being at the one end of the body portion and the blades 8 and 9 at the 75 opposite end. The blades 7 and 9 have counterweights 10 and 11 respectively at their free ends which assist the latter in assuming a vertical position as they reach a 80 position to be driven by a draft of air, as will now be explained.

75 By reference to Figures 1, 2 and 3, it will be noted that normally when no draft of air is upon the wind wheel, all of the blades or vanes 6, 7, 8 and 9 are inclined transversely. As soon as a draft of air is directed against the wind wheel one pair of blades or vanes immediately assumes a vertical position transversely while the other set or pair assumes a horizontal position transversely 90 which is a feathering position, and permits the wind wheel to turn half way around when this last-named pair of blades or vanes will assume a vertical position. These changing positions from vertical to horizontal of the blades or vanes is permitted by the pivotal action of the body portion 12 on the shaft 3, and said pivotal movement is limited by the body portion engaging the vertical shaft 2 so that it is impossible to 100 pivot or turn the blades a distance greater than that which is necessary to bring them to an approximate vertical position.

105 While I refer to horizontal and vertical positions of the blades, it is, of course, to be understood that this language refers merely to the movement of the blades transversely as they are always maintained at an angle or inclination longitudinally and the pairs of blades or vanes at each end of the body por- 110

tion are at an angle to each other. By reason of this construction the blades or vanes at one side of the wheel receive the full force of the draft of air while the 5 blades or vanes at the other side of the wheel are in a feathering position until they reach a point where they in turn assume a vertical position transversely and receive the full blast of air.

10 It will be noted that when the wind wheel is in operation, the vertically disposed blades or vanes will be in horizontal plane below the plane of the bearing sleeve, while the blades or vanes at the other end will 15 be in a horizontal plane above the horizontal plane of the bearing sleeve. This is shown clearly in Figure 4. When the wind wheel swings around, the force of the air assisted by the tendency of the blades or vanes to 20 balance each other, will compel the blades or vanes which have been above the horizontal plane of the bearing to fall to a vertical position below the horizontal plane of the bearing and elevate the other pair of blades 25 or vanes. In other words, the blades or vanes alternately shift from a plane above the plane of the bearing to a plane below and in so doing, move from a normally horizontal position to a normally vertical position 30 having reference to the transverse dimension of the blades or vanes.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

40 I claim:

1. A wind wheel, having a horizontal bearing and a vertical pivot, a pair of blades or vanes on each end of the wind wheel, the 45 pair of blades or vanes on one end of the wind wheel, when the latter is in operation, being located below the horizontal plane of the horizontal bearing, and the other pair

of blades or vanes being in a plane above said horizontal bearing.

2. A wind wheel, comprising an intermediate body portion, a bearing sleeve extending longitudinally of the body portion, and a pair of angularly disposed blades or vanes extending from each end of the body portion. 55

3. A wind wheel having a horizontally disposed bearing at its intermediate portion, a pair of angularly disposed blades or vanes extending from each end of the body portion, and counterweights on one blade of 60 each pair of blades or vanes.

4. The combination with a vertical drive shaft, and a horizontal shaft at the upper end thereof, of a wind wheel having a body portion provided with a horizontal bearing 65 at its intermediate portion supported on the horizontal shaft, and a pair of inclined and angularly disposed blades or vanes extending from each end of the body portion. 70

5. The combination with a vertical drive shaft, and a horizontal shaft at the upper end thereof, of a wind wheel having a horizontal bearing at its intermediate portion supported on the horizontal shaft, inclined blades or vanes extending from the 75 ends of the body portion, and said body portion at a right angle and adapted to engage the vertical shaft to limit the turning movement of the wind wheel on the horizontal shaft. 70

6. The combination with a vertical drive shaft, and a horizontal shaft at the upper end thereof, of a wind wheel having a horizontal bearing at its intermediate portion supported on the horizontal shaft, 85 inclined blades or vanes extending from the ends of the body portion, said body portion bent at a right angle and adapted to engage the vertical shaft to limit the turning movement of the wind wheel on 90 the horizontal shaft, and counterweights on the ends of certain of said blades or vanes. 85

GEORGE VAIL.
